ORGANOMAGNESIUM COMPLEXES HAVING ENHANCED STORAGE STABILITY

Francis H. Bratton, Northfield, Minn., and Francis J. Buescher, Alfred H. Frye, and Victor G. Soukup, Cincinnati, Ohio, assignors to The Cincinnati Milling Machine Co., Cincinnati, Ohio, a corporation of Ohio
No Drawing. Filed June 13, 1962, Ser. No. 292,052
17 Claims. (Cl. 266—665)

This invention relates to stabilized organomagnesium complexes and to a process for their preparation.

As used herein, the term "organomagnesium complex" refers to magnesium containing organic compounds in which the magnesium atom is bound directly to at least one carbon atom by a bond which is predominantly covalent in character. Examples of such organomagnesium complexes are the classical Grignard reagents or the magnesium dialkyls or diaryls, the latter two being illustrated by dibutyl magnesium and diphenyl magnesium.

It is known that organomagnesium complexes leave much to be desired from the standpoint of storage stability. To measure deterioration or instability a test was devised which is herein referred to as a stability test. In accordance with this test the organomagnesium complex in a normally liquid medium is placed in containers which are closed to the atmosphere and kept in the dark at the ambient temperature (about 25° C.) for a period of four weeks. The containers are opened to the atmosphere in the light for one five minute interval in the one day test and twice a week for the tests of longer duration. One container of material is used for each analysis. The analyses are carried out at least 24 hours after exposure. Initial values were established from unexposed samples which were analyzed for activity. The containers used in this test are wide-mouth, screw-cap, clear glass bottles of either 12 ounce (354 ml.) or 16 ounce (473 ml.) size.

Each test is performed in such a way that the air space in the capped bottle is 100 ± 5 ml. In other words, the total volume of the condensed phases (i.e., solids plus liquids) amounts to 255 ± 5 ml. in the 12 ounce bottles or 370 ± 5 ml. in the 16 ounce bottles. Adjustment of the volume of the condensed phases to the desired volume is achieved in the following three ways:

- (1) Glass marbles are added to increase the volume,
- (2) Additional hydrocarbon is added to increase the volume, or
- (3) In cases where the volumes of the condensed phases are too great, the contents of the bottles are allowed to settle and the excess supernatant liquid is removed by pipette and assayed for organomagnesium content.

During the periods when the test bottles are uncapped and exposed to the atmosphere, they are removed from the dark room or cabinet where they are normally stored and the exposure takes place under normal laboratory illumination (daylight plus fluorescent ceiling lights). After the exposures are complete the bottles are returned to the dark room or cabinet. The final analyses are always performed under normal laboratory illumination.

Organomagnesium complexes (Grignard reagents, dialkyl-magnesiums, diarylmagnesiums, etc.) are known to be decomposed by reaction with various normal atmospheric components, viz., water, carbon dioxide and oxygen. The stoichiometry of these reactions may be written as follows:

where R represents the organic radical and X is halogen.

2

By means of the Gilman method of analysis it is not possible to distinguish between "active" organomagnesium complex and the products formed by the interaction of the reactive components in the atmosphere with the "active" organomagnesium complex, the Gilman method being essentially an analysis for magnesium bases. Thus, in the Gilman analysis one treats the sample of organomagnesium complex with an excess of dilute hydrochloric acid and then determines the amount of excess hydrochloric acid present by titration with standard sodium hydroxide solution [H. Gilman, P. D. Wilkinson, W. P. Fischel and C. H. Meyers, J. Am. Chem. Soc., 45, 150 (1923)]. Since the decomposition of the organomagnesium complexes under the conditions of the present stability studies is most plausibly rationalized as resulting from their attack by atmospheric components during (and following) the periods of atmospheric exposure, it is obvious that the Gilman method of analysis would not be useful. A method was employed, therefore, in which the sample to be analyzed is subjected to carboxylation by treatment with "Dry Ice" (solid carbon dioxide) in an ethereal medium and the amount of carboxylic acid formed then determined by acid-base titration, the pertinent equations being:

(It is, of course, obvious that analysis by this carboxylation technique cannot distinguish between the organomagnesium complex which has reacted with atmospheric carbon dioxide and that which has reacted with the "Dry Ice," however the small amount of carbon dioxide normally present in the atmosphere warrants neglect of this factor.)

According to this procedure, the cap of the bottle, in which the sample was stored, is removed and in its place is inserted a rubber stopper through which run two pieces of $\frac{1}{4}$ inch glass tubing.

The tubing extends but slightly beyond the lower surface of the stopper and serves initially to displace the air in the bottle with nitrogen. After permitting a gentle stream of nitrogen to flow through the bottle for 5 minutes, the stopper is carefully lifted and approximately 75–100 ml. of sodium-dried ether (or, in certain instances, tetrahydrofuran) are introduced into the bottle and the stopper reinserted. The bottle is then swirled to cause dissolution of the organomagnesium complex. Meanwhile, in a 4-liter beaker there is placed approximately 1 liter of crushed Dry Ice, together with sufficient sodium dried ether (or tetrahydrofuran in some cases) to furnish a slurry. The outlet tube in the rubber stopper is then pushed to the bottom of the storage bottle and the ethereal solution of the organomagnesium complex caused to flow through that tube and into the beaker containing the ether and the Dry Ice, the Dry Ice-ether mixture being thoroughly stirred during the addition. In order to insure the quantitative transferral of all the organomagnesium complex to the beaker, two additional portions (ca. 300 ml. each) of sodium dried ether (or tetrahydrofuran) are carefully added in sequence to the bottle and the solution then expressed into the beaker. Finally, a fourth portion of ether (or tetrahydrofuran) is added to the bottle together with some Dry Ice, the mixture stirred and poured into the 4-liter beaker. The contents are then thoroughly stirred and allowed to stand uncovered overnight in the fume hood, during which time the bulk of the ether evaporates.

The next day, the residue in the beaker (a dry, grey cake) is stirred with 6–8 cubes of ice until the mixture is reasonably well dispersed, whereupon an excess of approximately 1-N hydrochloric acid is added and the mixture transferred to a 500-ml. separatory funnel. The

aqueous layer is withdrawn and the organic material remaining in the flask washed with several small portions of water, the washings being combined with the aqueous layer. The aqueous layer is then extracted with two 50-ml. portions of heptane and the heptane extracts combined with the organic layer, the combined material transferred to a 250-ml. volumetric flask, and the contents made up to the mark by the addition of ether. After shaking the mixture thoroughly, a 25-ml. aliquot is withdrawn and titrated with 0.1-N sodium hydroxide solution to determine the amount of carboxylic acid present therein. From this information, together with information bearing on the amount of carboxylic acid which can be obtained from a standard freshly prepared organomagnesium complex, one can calculate the amount of organomagnesium complex which has deteriorated under the test conditions.

One milliequivalent of active organomagnesium complex furnishes in theory one milliequivalent of carboxylic acid in the above procedure.

When solutions of various Grignard reagents in ether type solvents were subjected to the foregoing stability test, it was noted that the reduction in activity was practically a straight line function of the time and at the end of the four week period more than half of the initial activity had been lost.

One of the objects of the invention is to provide compositions containing organomagnesium complexes which are sufficiently stabilized to permit containers containing these compositions to be stored and subjected to intermittent atmospheric exposure over a period of at least four weeks while still retaining a major proportion, and preferably at least 70%, of the initial activity.

A further object of the invention is to provide a method and compositions for enhancing the storage stability of organomagnesium complexes so that they can be sold as such and used as desired in carrying out chemical reactions by withdrawing them from storage at intervals without taking any unusual precautions during the storage period.

Another object of the invention is to provide organomagnesium complexes of enhanced stability in which the hazard associated with such complexes is vastly less than that with the highly flammable and even explosive ethers of the conventionally prepared organomagnesium complexes.

A more specific object of the invention is to provide a new and improved method for stabilizing organomagnesium complexes which retards loss of the activity of the organomagnesium complexes on storage.

Another specific object is the provision of new and improved stabilized compositions containing organomagnesium complexes. Other objects will appear hereinafter.

In accomplishing these objects in accordance with the invention it has been found that enhanced storage stability is obtained by preparing compositions which consist essentially of ether-free organomagnesium complexes in hydrocarbon media, which media may be either individual inert hydrocarbon compounds or mixtures of such compounds, but which media are liquid at room temperature (about 25° C.), and which, when slurried with an excess of the organomagnesium complexes at 25° C. and the slurries then allowed to settle until their supernatant liquid phase separates, have supernatant liquid phases in which the concentrations of the organomagnesium complexes do not exceed 35 milliequivalents (meq.) per 100 ml. of the liquid phase, and preferably do not exceed 10 milliequivalents of organomagnesium complex per 100 ml. of the liquid phase.

The invention will be further illustrated but is not limited by the following examples in which the quantities are stated in parts by weight unless otherwise indicated.

In these examples various ether-free organomagnesium complexes were prepared in liquid hydrocarbon media. Samples of the compositions were placed in closed con-

tainers under substantially identical conditions and stability tests were carried out with exposure to the atmosphere as follows:

Storage time:

	conditions
5	1 day ---- Sample given a 5-minute exposure to the atmosphere and analyzed after at least 24 hours
10	1 week --- Sample given two 5-minute exposures spaced at equal intervals during the week
15	2 weeks -- Sample given four 5-minute exposures spaced at equal intervals during the 2 weeks
20	4 weeks --- Sample given eight 5-minute exposures spaced at equal intervals during the 4 weeks

Hence a four week stability test represents a minimum of eight container openings and a total time of exposure of the organomagnesium complex to the atmosphere of 40 minutes. The discontinuous exposure, namely, that of eight exposures of five minutes each, provides eight separate new atmospheres to the complex, each being present for a prolonged reaction period. In effect this is the same as if a user were to make eight separate withdrawals of material from the container over a four week period. The test is intended to simulate the typical conditions that might be encountered in commercial usage.

The following results were obtained:

Example	Composition	Concentration of organomagnesium complex in supernatant hydrocarbon medium
35		
I	Organomagnesium complex prepared from butyl chloride and magnesium in heptane: 1 day--92% remaining 1 week--89.3% remaining 2 weeks--81.7% remaining 4 weeks--81.7% remaining	0.2 meq./100 ml.
40		
II	Organomagnesium complex prepared from octyl chloride and magnesium in heptane: 1 day--89.8% remaining 1 week--88.8% remaining 2 weeks--75.3% remaining 4 weeks--69.6% remaining	15.6 meq./100 ml.
45		
III	Organomagnesium complex prepared from phenyl chloride and magnesium in Stoddard solvent: 1 day--97.5% remaining 1 week--97.4% remaining 2 weeks--95.5% remaining 4 weeks--88% remaining	1.9 meq./100 ml.
50		
IV	Organomagnesium complex prepared from butyl chloride and magnesium in cyclohexane: 1 day--95.3% remaining 1 week--90.6% remaining 2 weeks--73.6% remaining 4 weeks--69.7% remaining	33.0 meq./100 ml.
55		
V	Organomagnesium complex prepared from butyl chloride and magnesium in a 1:1 ratio (volume) cyclohexane-heptane: 1 day--99.5% remaining 1 week--94.7% remaining 2 weeks--85.5% remaining 4 weeks--85.4% remaining	6.2 meq./100 ml.
60		
VI	Organomagnesium complex prepared from butyl chloride and magnesium in 2,2,4-trimethylpentane: 1 day--100% remaining 1 week--94.4% remaining 2 weeks--85.8% remaining 4 weeks--86.2% remaining	0.01 meq./100 ml.
65		
VII	Organomagnesium complex prepared from phenyl chloride and magnesium in cyclooctane: 1 day--100% remaining 1 week--92% remaining 2 weeks--86.0% remaining 4 weeks--85% remaining	9.7 meq./100 ml.

Example	Composition	Concentration of organomagnesium complex in supernatant hydrocarbon medium
VIII	Organomagnesium complex prepared from α -chloronaphthalene and magnesium in odorless mineral spirits: 1 day—100% remaining 1 week—95% remaining 2 weeks—88% remaining 4 weeks—86% remaining	0.0 meq./100 ml.

For comparative purposes, stability tests were carried out with various organomagnesium complexes in diethyl ether and in tetrahydrofuran as follows:

Example	Composition	Concentration of organomagnesium complex in the ethereal medium
IX	Organomagnesium complex prepared from butyl chloride and magnesium in diethyl ether: 1 day—91.5% remaining 1 week—85.5% remaining 2 weeks—73% remaining 4 weeks—38% remaining	175 meq./100 ml.
X	Organomagnesium complex prepared from octyl chloride and magnesium in diethyl ether: 1 day—94.5% remaining 1 week—88% remaining 2 weeks—74% remaining 4 weeks—42% remaining	221 meq./100 ml.
XI	Organomagnesium complex prepared from phenyl chloride and magnesium in tetrahydrofuran: 1 day—84.5% remaining 1 week—64% remaining 2 weeks—47% remaining 4 weeks—34% remaining	234 meq./100 ml.

From Examples IX, X and XI which are outside of the scope of the present invention it will be seen that the organomagnesium complex deteriorated rapidly in liquids such as diethyl ether and tetrahydrofuran when tested in accordance with the previously described stability test.

Although one form of the composition is a slurry of an organomagnesium complex in hydrocarbon media, the invention is not limited to slurries but also covers pastes and even compacted cakes of these organomagnesium complexes immersed in or otherwise associated with the hydrocarbon media. The pastes can be obtained from the slurries by centrifugation and the cakes from the pastes by compression in a die. A typical compacted organomagnesium complex was prepared in this manner by the interaction of butyl chloride and magnesium chips in heptane and was found to contain the following.

Ingredients:	Percent by weight
Heptane	61-64
Organomagnesium complex ¹	26-29
Unreacted magnesium	2-3
Magnesium chloride	6-7

¹ The organomagnesium complex was assumed to be C_8H_7MgCl for the purpose of this calculation.

In this composition the compacted organomagnesium complex was totally immersed in the hydrocarbon medium.

In general the compositions prepared in accordance with the invention will contain a maximum of 70% by weight organomagnesium complex and preferably a minimum of 5% by weight organomagnesium complex, the remainder being a hydrocarbon or mixtures of hydrocarbons, liquid at 25° C. Where the organomagnesium complex is a Grignard reagent, the composition can also contain unreacted magnesium and a magnesium halide, the quantity of the unreacted magnesium preferably not exceeding 5% and the quantity of the magnesium halide (e.g., magnesium chloride, magnesium bromide or magnesium iodide) preferably not exceeding 10%.

The invention is applicable to all types of organomagnesium complexes involving at least one carbon-magnesium bond having a predominantly covalent character. It is especially useful in connection with organomagnesium complexes which are normally made by reacting an organic halide such as a chloride, bromide or iodide with magnesium. In addition to the specific illustrations given in the examples, it will be understood that the invention is applicable to a large number of other organomagnesium complexes, including by way of example but without limitation, those in which the organic groups are methyl, ethyl, n-propyl, isopropyl, cyclohexyl, allyl, and vinyl. The organic radicals can be alkyl, alkenyl, alkynyl, aralkyl, alkaryl or aryl.

15 The organomagnesium complexes can also be prepared by methods such as the addition of olefins to magnesium hydride or by the interaction of mercury alkyls or aryls with metallic magnesium.

16 The hydrocarbon medium should be one which is liquid at room temperature (25° C.), a number of illustrations of which have been previously given in the examples. Especially good results have been obtained by using aliphatic hydrocarbons or alicyclic hydrocarbons, or mixtures thereof containing five to ten carbon atoms.

20 25 The compositions described herein, viz., slurries, pastes, suspensions, dispersions, or compacted cakes of solid, ether-free organomagnesium complexes in liquid hydrocarbon media, afford numerous practical advantages relative to storage, shipping, and usage over conventional

30 35 ethereal Grignard reagents. An especially important advantage of the compositions is that they permit the storage vessel to be repeatedly opened and closed for withdrawal of portions of the organomagnesium complex as needed without incurring its undue decomposition by reactive components in the atmosphere, viz., oxygen, carbon dioxide, and water. A further advantage of the compositions is that the hazard associated with the hydrocarbon media is vastly less than that with the highly flammable and even explosive ethers of the conventionally prepared

40 45 Grignard reagents.

The invention is hereby claimed as follows:

1. A composition of enhanced storage stability consisting essentially of a mixture of an ether-free organomagnesium complex in a quantity of a liquid hydrocarbon medium sufficient to permit the presence of a supernatant liquid phase when the mixture is allowed to settle, the hydrocarbon medium being one which is normally liquid at room temperature and which when slurried with the organomagnesium complex at 25° C. and the slurry then allowed to settle gives a supernatant liquid phase in which the concentration of the organomagnesium complex does not exceed 35 milliequivalents per 100 milliliters of the liquid phase.

2. A composition of enhanced storage stability consisting essentially of a mixture of an ether-free organomagnesium complex in a quantity of a liquid hydrocarbon medium sufficient to permit the presence of a supernatant liquid phase when the mixture is allowed to settle, the hydrocarbon medium being one which is normally liquid at room temperature and which when slurried with the organomagnesium complex at 25° C. and the slurry then allowed to settle gives a supernatant liquid phase in which the concentration of the organomagnesium complex does not exceed 10 milliequivalents per 100 milliliters of the liquid phase.

3. A composition as claimed in claim 1 in which said hydrocarbon medium is a liquid mixture of hydrocarbons.

4. A composition as claimed in claim 1 in which said hydrocarbon medium is from the group consisting of aliphatic and alicyclic hydrocarbons containing 5 to 10 carbon atoms and mixtures of such hydrocarbons.

5. A composition as claimed in claim 1 but in which the organomagnesium complex is compacted into cakes which are totally immersed in the hydrocarbon medium.

6. A composition as claimed in claim 1 in which there

is between a minimum of 5% and a maximum of 70% by weight of said organomagnesium complex.

7. A composition of enhanced storage stability consisting essentially of a mixture of an ether-free organomagnesium complex formed from the interaction of an organic halide with magnesium and a quantity of a hydrocarbon medium liquid at 25° C. sufficient to permit the presence of a supernatant liquid phase when the mixture is allowed to settle, the hydrocarbon medium being one which when slurried with said organomagnesium complex at 25° C. and allowed to settle gives a supernatant liquid phase in which the concentration of the organomagnesium complex does not exceed 35 milliequivalents per 100 milliliters of the liquid phase.

8. A composition of enhanced storage stability comprising a mixture of a minimum of at least 5% by weight and a maximum of not more than 70% by weight of an ether-free organomagnesium complex formed from the interaction of an organic halide with magnesium and a quantity of a stabilizing medium which is liquid at 25° C. sufficient to permit the presence of a supernatant liquid phase when the mixture is allowed to settle, said stabilizing medium consisting essentially of at least one hydrocarbon which is liquid at 25° C., said hydrocarbon when slurried with said organomagnesium complex at 25° C. and allowed to settle giving a supernatant liquid phase in which the concentration of said organomagnesium complex does not exceed 35 milliequivalents per 100 milliliters of the liquid phase, the amount of said hydrocarbon liquid being sufficient to enhance the storage stability of said organomagnesium complex.

9. A composition as claimed in claim 8 in which the organomagnesium complex is formed from a primary alkyl chloride and magnesium.

10. A composition as claimed in claim 8 in which the organomagnesium complex is formed from an aryl chloride and magnesium.

11. A process of enhancing the storage stability of an ether-free organomagnesium complex which comprises forming a mixture of such complex with a quantity of a liquid hydrocarbon medium sufficient to permit the presence of a supernatant liquid phase when the mixture is allowed to settle, the hydrocarbon medium being one which is liquid at 25° C. and which when slurried at 25° C. with said organomagnesium complex and the slurry allowed to settle gives a supernatant liquid phase in which the concentration of the organomagnesium complex is not in excess of 35 milliequivalents per 100 milliliters of said liquid phase, the quantity of said hydrocarbon being

sufficient to enhance the storage stability of said organomagnesium complex.

12. A process of enhancing the storage stability of an ether-free organomagnesium complex which comprises forming a mixture of such complex with a quantity of a liquid hydrocarbon medium sufficient to permit the presence of a supernatant liquid phase when the mixture is allowed to settle, the hydrocarbon medium being one which is liquid at 25° C. and which when slurried at 25° C. with said organomagnesium complex and the slurry allowed to settle gives a supernatant liquid phase in which the concentration of the organomagnesium complex is not in excess of 10 milliequivalents per 100 milliliters of said liquid phase, the quantity of said hydrocarbon being sufficient to enhance the storage stability of said organomagnesium complex.

13. A process as claimed in claim 11 in which a mixture of hydrocarbons liquid at 25° C. is used.

14. A process as claimed in claim 11 in which the hydrocarbons liquid at 25° C. are from the group consisting of aliphatic and alicyclic hydrocarbons and mixtures thereof containing 5 to 10 carbon atoms, inclusive.

15. A process as claimed in claim 11 in which the organomagnesium complex is an ether-free organomagnesium complex formed from the interaction of an organic halide with magnesium.

16. A process as claimed in claim 11 in which the organomagnesium complex is a Grignard reagent derived from a primary aliphatic chloride and magnesium.

17. A process as claimed in claim 11 in which the organomagnesium complex is a Grignard reagent derived from an aryl chloride and magnesium.
